UNITED STATES PATENT OFFICE.

HENRY STAMM, OF PLAUE, GERMANY, ASSIGNOR TO THE FIRM OF FERD. ASHELM BUCHDRUCKEREI, OF BERLIN, GERMANY.

MACHINE FOR THE PRINTING OF CALENDARS, CASH-BLOCKS, TICKET-BLOCKS, OR THE LIKE.

SPECIFICATION forming part of Letters Patent No. 786,852, dated April 11, 1905.

Application filed July 11, 1904. Serial No. 216,144.

To all whom it may concern:

Be it known that I, HENRY STAMM, a citizen of Switzerland, and a resident of Plauen, Germany, have invented certain new and useful 5 Improvements in Machines for Printing Calendars, Cash-Blocks, Ticket-Blocks, or the Like, of which the following is a description, such as will enable others skilled in the art to which it appertains to make and use the same.

10 This machine is designed for the purpose of printing calendars from which every day a sheet is torn off, cash-blocks, ticket-blocks, and the like by rotary printing, so that in one manipulation and with one stereotyping the individual calendar-dates are delivered from the machine all cut and arranged in their proper order, so that the manual labor required until now for the arranging and cutting of the blocks is completely done away with. The 15 printing-surface of the cylinder is so calculated that the totality of the leaves of a calendar can be contained on it. This requires a comparatively large-size rotary machine as well as a cylinder of considerable diameter 20 and a very large breadth of paper-roll. All that is then necessary is that the printed paper shall be cut up by means of cross and longitudinal cuts into the individual leaves and then the same collected together and 25 formed into blocks, all these operations to be performed automatically. Besides this the machine must deliver different-sized blocks, but work the same as a rotary machine for an unchangeable size, and the print is cut up into 30 small pieces after and not before the printing. With different sizes only the width of the paper-roll and the division of the sentences will change. The cylinder will always remain the same and must be printed around the whole 35 40 of its circumference. The difference in size is obtained by changing two pairs of cog-wheels in the cutting and collecting device so that these devices are turned through a greater or less distance, whereby none of the parts of 45 the cutting or collecting device are changed even if cuts of different length are required.

I will now describe my invention with reference to the accompanying drawings, in which—

50 Figure 1 is a vertical section through the

machine. Figs. 2 and 3 are details more particularly hereinafter referred to. Fig. 4 is a transverse section through the case. Fig. 5 is an enlarged section through the eccentric and the shaft of the delivery-cylinder. Fig. 55 6 is a view at right angles to Fig. 5 with parts in section and portions broken away.

As shown by Fig. 1, the paper *a*, coming from the paper-roll, runs first onto the first impression-cylinder *b* and then onto the second impression-cylinder *c*, where it is printed in two colors by two cylinders *d* and *e* and then cut into the required breadth by circular cutters while it is conducted over the guide-cylinders *g* and *h* through the pair of cutting-cylinders *i* and *k*. *i* is the so-called "cutting-cylinder" and *k* the "groove-cylinder." Both can be of any desired size and have any desired number of cutters or grooves, provided that the distance between the cutters or 60 grooves on the circumference of the cylinder is at least equal to the longest required cut of the different sizes of calendars. These cutting-cylinders cut the broad paper into small 65 slips crosswise to the longitudinal direction. The width of these strips—that is, the so-called "length of cut"—is equal to either the height or breadth of the required block. If a smaller size is required than the distance 70 between the knives cut, then the pair of cutting-cylinders *i* and *k* are made to turn correspondingly quicker, so that for every turn of the printing-cylinder always a definite number of cuts, changing according to the size, are 75 made. The greater the number of cuts the 80 smaller will be the length of the cut—that is to say, the width of the individual cross-strips. Inasmuch as the cutting-cylinders, except in the largest size, revolve quicker than the paper they do not touch each other, but allow 85 the paper to pass freely between them. The cutting-cylinders work thus in a somewhat similar way to the cutting-cylinders of a rotary machine for different sizes with the exception, however, that the cut is not made before printing, but after printing. Another 90 difference is that the speed of the cutting-cylinders varies according to the size block required instead of the invariable speed with 95 rotary machines for different sizes. The very 100

wide paper necessitates a cutting-cylinder of large diameter if it is to work exactly and not fray the edges. The great difficulty that arises with very short cuts in comparison to 5 the diameters of the cutting-cylinders is to securely and in a simple manner gather up the short strips and bind them together. This is obtained by means of a band-guide l , which runs over a small spindle m , receives the 10 small strips, and accompanies them for a short distance around the groove-cylinder k . Close to the groove-cylinder k the collecting-cylinder n is placed, the speed of which is equal to that of the cutting-cylinders and has rows 15 of pricks or puncturing-points o , the rows being separated from each other by a distance equal to that which separates the cutters or grooves of cylinders i or k , respectively. A small hole is bored in the groove-cylinder k exactly opposite each puncture-point, into which the point passes. The strips as they leave the groove-cylinder k and run onto the collecting-cylinder n are transfixed by the pricks or points o , so that they remain hanging on the 20 circumference of the collecting-cylinder and make several revolutions with it. The adjustable tongues p of the collector, moreover, guarantee the proper guidance of the strips. Each row of pricks receives a new strip of paper at 25 every turn of the collector n . After each period—that is to say, after every turn of the printing-cylinder—one of the packets collected in one of the rows of points is removed by the cylinder q , whereupon this row of points 30 again commences to collect other strips of paper to form a fresh packet or block, while the packets on the other rows of points are gradually completed. Each row of points collects as many strips as are printed at each 35 revolution of the form-cylinder. The cylinder q has one or more rows of points, only one of which comes into use for each revolution of the form-cylinder. The removal of the strips from the collector n to the cylinder 40 45 q is occasioned by the respective points at the stop where the cylinders touch each other drawing back into the interior of the collector, thus releasing the packet, which is then seized by the points of the cylinder q . This cylinder q is swung pendulumwise, owing to its having to make several revolutions before it comes into work, and by means of an eccentric r , eccentric-rod s , and lever t it approaches the collector n once for each period, so as to 50 55 broach the packet released by the collector. One row of points in the cylinder q is sufficient if its circumference is smaller than the circumference of the collector by one dividing cut for that cut whose number during 60 a period or during one revolution of the form-cylinder is a whole number and not a fraction. If this is not so, then this cylinder must have just as many rows of points as are contained in that of the collector n relatively 65 to its circumference. Only one of the rows

of points of the collector work at one and the same time for each revolution of the form-cylinder, the other rows being drawn back in the interior of the cylinder. The points are moved—that is, pushed out or pulled back in 70 the interior of the collector or delivery-cylinder—in the usual way by levers u , which are situated on a longitudinal axle v , Fig. 5, one for each row. This movement is obtained by means of a separate eccentric w for each row, 75 the rotation number of which is equal to $\frac{1}{(a)}$ of a period, so that the rows of points are brought into working one after the other—that is, one eccentric for each period. Some- 80 what similar devices have often been used with printing-machines, so that it is not necessary to go into any further details here. The packets could be collected by fixed rows of points on the collector, as is the case, for example, in newspaper rotary machines. In such a case the removal of the packet to the cylinder q is brought about by the aid of tongues x , Fig. 2, which engage in grooves on the collecting-cylinder just in front of the 85 packet, and after the removal of the latter the tongues x immediately disengage from the grooves; but in this case the individual packets must be separated from each other by some considerable distance in order that the 90 tongues x can have the time to engage in the grooves of the collecting-cylinder. On this account the speed of the collector-cylinder in this kind is considerably greater, and therefore the productive power of the machine is 95 somewhat less than when the packets are removed by movable rows of points, as described above. No points are required by the delivery-cylinder when the tongues x , Fig. 2, 100 are employed. 105
Instead of the points that draw back fixed points could also be used, whereby the removal of the packets to the cylinder is obtained by means of grips, Fig. 3, such as are often made use of in rotary machines. These grips are actuated in a somewhat similar way to the movable points described above, so that always only one row is removed at each 110 revolution of the cylinder. In the way described the totality of the strips which are 115 cut after one revolution of the cylinder are collected into a packet, and the time for the formation of a single packet lasts through as many revolutions of the form-cylinder as the 120 number of rows of points in the collector—that is, the time of a revolutions of the form-cylinder, because a in the above example corresponds to the number of rows of points in the collector. The packet of strips formed at each revolution of the form-cylinder are removed by the cylinder q by means of a band z and by means of a lifting-rod 1 are thrown 125 down into the case 2 . As in the present case the work must be exact, as any displacement would result in the packet not being formed, a 130

special device 3 works in conjunction with the lifting-rod 1. This consists of a row of rods somewhat similar to the lifting-rod 1 and arranged immediately under the band 2. The 5 packets of strips are held for a moment between the band 2 and the rods 3 as soon as ever they strike against the projection 4 of the case 2. The packet of strips, the lengths of which are equal to the width of the roll 10 of paper, find the required support in the rods of the device 3, said rods being slightly separated from each other and as near as possible to the bottom of the box 2, so that the packets only falling such a slight distance 15 cannot be displaced when the device 3 swings into the position shown in dotted lines, Fig. 1, while the rods 1 at the same time press firmly on the packets already laid in front of them. During their pressure the rods of the 20 device 3 reassume their former positions, as shown in Fig. 1 in full lines, and prevent the strips jumping up when the rod 1 is raised. Each packet of strips, such as are collected in each period, contains, as has already been 25 stated, all the dates of a complete calendar; but in order to form a proper block it must then be cut up into small pieces by a number of cross-cuts, so as to assume the form of a block, and the different small packets thus 30 formed must be collected together to form the required block. This is obtained as follows: The bottom of the case 2 consists of an endless band 5, intermittently moving in a cross direction to that of the paper coming 35 from the roll that is in the longitudinal direction of the strips. One edge of this band 5 is provided with points on which the packet of strips is stuck, owing to the pressing of the rod 1. As soon as this has happened the 40 band 5 is moved sidewise the width of the required block, together with the strips stuck onto it, the individual strips lying like stairs one on the other. In order to assure the exact moving of the band 5, this movement can 45 be so arranged during the pressing of the rod 1 on the packet that the rod also makes a side movement with the band, afterward rising and returning to its normal position. If the different parts into which the packet of strips 50 have to be cut up are numbered, for example, 1 2 3 4 5 6, and if such a row of numbers of the strips are arranged, then the packets will lie one over the other, as follows:

	1 2 3 4 5 6	I	II	III	IV
55	1 2 3 4 5	6			
	1 2 3 4	5	6		
	1 2 3	4	5	6	
	1 2	3	4	5	6
60	1	2	3	4	5 6
	1	2	3	4	5 6
	1	2	3	4 5	6
	1	2	3 4	5	6
	1	2 3	4	5	6

The top row of numbers shows the last 65 packet of strips collected, which after a fur-

ther period reaches the first vertical row 1 in the above example, then the second row, and then the third row. On arriving at the last row 4 the packet is considered to be already 70 cut up. Then comes a cut along the third row, then the second, and so on, each cut separated by a period, so that parts 1 2 3 4 5 6 always lie one above the other, and so form complete blocks.

The plan of the processes referred to together with the parts for the further preparation of the blocks is shown in Fig. 4, which presents a section of the case 2 crosswise to the running direction of the paper. 6 and 7 are small rolls of paper, from which both 80 covers of the blocks are prepared. The endless band 5, forming the bottom of the case 2, is provided with points 8 and runs around two rollers 9 and 10, which are intermittently moved in the direction of the arrow by means 85 of a ratchet-wheel (not shown) or other suitable device. The above-mentioned packets of strips are situated on this band in the form of stairs. By lowering the press-beam 11 the end of the packet is firmly pressed against 90 the support for a moment while the cap-holder 12 pushes back a metal cap 14, pressed forward by a rod 13 by a quarter-revolution on to the cut end of the packet. Then the binding device 15 lowers itself from above 95 and binds the rough end and the metal cap together with a wire clamp. At the same time the lower bent edge of the metal cap is bound by a wire clamp by means of binding device 16. These binding devices work with 100 an endless wire in a similar way to the ordinary well-known wire-binding machine, and a further description here is therefore unnecessary. As soon as the rough end is bound, and consequently no further danger of being 105 displaced, the knife 17 cuts and separates the completed blocks. A pusher 18 and a gripper 19 are moved so that the block is pulled forward, in which position the sides of the block are trimmed by a pair of cutters 20 110 and then pushed out by an arm or pusher working at the side, but not shown in the drawings.

As the different parts of the machine only come into action once for each revolution of 115 the form-cylinder, there is consequently but a relatively slow movement, even if the speed of the form-cylinder is as high as that in the ordinary rotary machines, so that it is possible to take advantage of the full production 120 power of rotary printing.

If it is desired to change the size, the intermediate gear-wheels 21, Fig. 1, which actuate the cutting and collecting device, are changed, and other wheels substituted of such 125 a diameter that the revolutions thereby obtained correspond to the required size of block. The change of size in the cross direction is obtained by a greater or less displacement of the band 5—that is, by displacement 130

of the pawl or catch 22 appertaining to the band 5, different-sized wheels being fitted to axle 23 to correspond to the different sizes. The distance separating the cutters 17 of the 5 binding device 15 16 will naturally be arranged to correspond to the desired size. The changing of the machine to suit the different sizes is thus exceedingly simple. Every turn of the printing-cylinder prints a complete calendar. If smaller calenders than the half of the largest size are required, naturally larger blocks could be printed and afterward cut up into smaller ones, so that the productive power of the machine could thereby be increased 10 15 two or more fold.

What I claim, and desire to secure by Letters Patent, is—

1. An improved machine for the manufacture of calendars, cash and ticket blocks and 20 the like in which the paper from the roll is printed by a rotary machine with all the date-leaves and then cut into cross-strips, the same comprising a collecting-cylinder *n*, cutting-cylinders *i*, *k* a band for conducting said strips 25 to said collecting-cylinder *n*, movable points, tongues or rows of "push-grips" on said collecting-cylinder and on which cylinder said strips are collected into blocks, a movable row of points, a delivery-cylinder having a cutter 30 17, a band *z*, a projection 4, a device 3, a rod 1, an intermittently-moved endless band 5, whereupon they are then brought under said cutter 17 which separates the individual blocks, substantially as herein described and set forth.
- 35 2. An improved machine for the manufacture of calendars, cash and ticket blocks and the like, in which the paper from the roll is printed by a rotary machine with all the date-leaves and then cut into cross-strips, the same 40 comprising a collecting-cylinder *n*, cutting-cylinders *i*, *k*, a band for conducting said strips to said collecting-cylinder *n*, movable points tongues or rows of "push-grips" on said collecting-cylinder, and on which cylinder said 45 strips are collected into blocks, a movable row

of points, a delivery-cylinder having a cutter 17, a band *z*, a projection 4, a device 3, a rod 1, an intermittently-moved endless band 5, whereupon they are then brought under said cutter 17 which separates the individual blocks, 50 a cap 14, a band 5, a binding device, a gripper 19, a rod 18, a pair of cutters 20, and a cap-holder 12 which at each quarter circular turn moves the metal cap to the printed paper block on the band 5 whereupon the cap 14 is 55 fastened by a wire clamp by the binding device 15, 16 and then the rod 18 moving to and fro with the gripper 19, brings the side edges under the pair of cutters 20 so as to be trimmed substantially as herein described and set forth. 60

3. An improved machine for the manufacture of calendars, cash and ticket blocks and the like in which the paper from the roll is printed by a rotary machine with all the date-leaves and then cut into cross-strips, the same 65 comprising a collecting-cylinder *n*, cutting-cylinders *i*, *k* a band for conducting said strips to said collecting-cylinder *n*, movable points, tongues or rows of "push-grips" on said collecting-cylinder and on which cylinder said 70 strips are collected into blocks, a movable row of points, a delivery-cylinder having a cutter 17, a band *z*, a projection 4, a device 3, a rod 1, an intermittently-moved endless band 5, whereupon they are then brought under said 75 cutter 17, which separates the individual blocks, a pair of cutting-cylinders *i*, *k* and a collecting-cylinder, the speed of which can be adjusted by changing the wheel 21 with a view to obtaining different-sized blocks and at the 80 same time to impart a greater or less movement to the endless intermittently-moved band 5 on which the blocks of strips are situated one above the other in the form of stairs substantially as herein described and set forth. 85

In testimony whereof I affix my signature.
HENRY STAMM.
